HENRY DOESKEN, OF LOS ANGELES, CALIFORNIA, ASSIGNOR OF ONE HALF TO CHARLES DE LE FOND, OF LOS ANGELES, CALIFORNIA

VEHICLE OPERATED GATE

Application filed November 13, 1929. Serial No. 406,346.

This invention relates to gates and has particular reference to a gate mechanism operable by an approaching vehicle to close or open the gate.

The general object of the present invention is to provide a simple, dependable and inexpensive device of the character described. More particularly my object is to provide, in such a device, only such instrumentalities as have been found reliable and durable. To this end my invention consists in the combinations hereinafter fully set forth and illustrated in the appended drawings, of which:

Fig. 1 is a front elevation of a device embodying the invention, and

Fig. 2 is a side elevation, on a larger scale, substantially in agreement with the foregoing view.

The structure of my invention comprises a hollow, vertical cabinet, or post 1, on the side of which a gate is pivotally hung. This gate consists of a barrier 2, rigidly mounted on a vertical member 3. The latter turns on pivots 4 and 5, and it is at the top provided with a bevel gear 6 in mesh with a bevel gear 7 of a transverse shaft 8.

Vertically slidable within the post 1 is a weighted member, or cage 20, and this cage is held suspended from a sprocket wheel 10 of the shaft 8 by means of a chain 9. Within the cage 20 is pivoted a short shaft 21, on which are mounted a drum 22 and a bevel gear 23. The latter is held permanently in mesh with a bevel gear 24 of an electric motor 25. One end of the chain 9 is attached to the drum 22 and the other end is secured to the top of the cage. When the motor 25 is energized it rotates the drum, thereby winding the chain onto the drum and elevating the cage. This is the normal position of the gate and cage at rest is indicated in Fig. 2. When the motor current is again disrupted and the cage otherwise released, it falls by its own weight. Because the chain 9 is hung on the sprocket 10, and the latter is rigid with the shaft 8 and the bevel gear 7, it is seen that this winding and unwinding of the drum and chain results in a rotation of said shaft in opposite directions and in corresponding movements of the gate barrier.

For the purpose of this description let it be assumed, that the structure of my invention is placed on a highway, at a railroad crossing, and that an electric line extends from the device a predetermined distance along the railroad track, terminating in a switch. As such circuit is well known and employed in railroad block signal systems, it is herein merely diagrammatically illustrated by a switch 30, which is closed by contact with the wheels of an approaching train, a source of electric energy 31, and a relay 32 of the type used in block signal systems.

The relay 32 controls a power circuit operating the structure, and this circuit is energized by a suitable source of electric power 15. From the latter extends a conductor to a switch 33, and this switch controls circuits through a solenoid magnet 34 and the motor 25. Wires from the other side of the power source 15 are shown leading to the opposite terminals of said solenoid and motor. On a drum of the cage shaft 21 is mounted a brake band 35, which is suitably connected to be operated by the plunger of the solenoid normally to maintain the cage elevated. In Fig. 2 the solenoid circuit is shown closed and the brake set.

A train reaches and closes the switch 30, thereby energizing the relay to break the solenoid circuit and to release the brake, permitting the cage to descend and to swing the gate to close the road which the train is about to cross. Now it is noticed, that a projection 12, of the chain, has held the switch 33 in position to maintain the solenoid circuit closed. The moment the cage commences to descend it is to be noted, that this projection begins to travel away, leaving the switch free to be thrown, by gravity or otherwise, and to close the motor circuit. However, so long as the rail switch 30 remains closed, the motor circuit is dormant, and the gate closed, until the train has passed the crossing and the switch 30 again is released. The power circuit then becomes energized, the motor starts up and commences to wind the chain up, to elevate the cage, and thereby to open the gate. The projection 12 again throws the switch 33, thereby breaking the

motor circuit and closing the solenoid circuit to set the brake.

In order to regulate the movement of the gate, which should ordinarily travel through an arc of ninety degrees, it is well to make the projection 12 adjustable on the chain. When the cage reaches the limit of its required downward movement, the chain is found to be entirely unwound, and further movement of the cage is thereby prevented. For the purpose of relieving strain on the chain, should the cage stay in this position for a protracted period of time, or if the chain is disconnected for inspection or replacement, suitable elements, such as projecting rests 11 may be provided in the wall of the post. Means should also be provided to guide the cage, and such means is shown to comprise a pair of guide rails 13, 14 engaging bifurcated projections of the cage.

From the foregoing description it is seen, that a circuit normally is closed through the solenoid 34, to hold the cage elevated and the gate open to transverse traffic. The electric devices employed are similar to those used in block signal systems and have proved to be dependable and durable. Should, however, an electric disruption appear at any place, such mishap will be seen to result in a release of and lowering of the cage, and a consequent closing of the gate. Nothing can occur within the device to prevent the gate from closing except, of course, a complete mechanical break down, which is not likely to happen, as such devices are subject to careful and periodical inspection.

Because more current is required to close the solenoid and to set the brake, than is needed to maintain this magnet closed, I prefer to provide an additional solenoid magnet 36, and to mount a switch 37 for operation by the plunger 38 of this magnet. In the drawings this plunger 38 is shown connected to open the switch 37 at the end of its upward stroke, thereby cutting out this magnet. Through the medium of a rocker 39 the two magnets are connected for simultaneous movement, and for this reason the plunger 38 is held elevated to maintain the switch 37 open so long as the main solenoid 34 remains energized. In this manner both magnets are employed to set the brake, but only one is required to maintain it set.

The gate of my invention swings in a horizontal plane, and one of the most important features of the invention is, that the gate is free to swing in either direction in response to pressure by any outside source, independent of the above described operating mechanism. Should a vehicle approach and strike the closed, or closing gate, no damage to gate or vehicle will result, where such collision would damage or destroy the ordinary types of railroad gate. This feature will now be more fully explained. The cage descends as

far as it can, to close the gate. If a collision should occur at this time, and the impact is in the same, closing direction, a further rotation of the sprocket wheel takes place and, because the chain is fully unwound, this rotation results in an elevation of the cage and a slackening of the chain on the opposite side of the sprocket wheel.

When an object strikes the gate from the opposite direction, such collision also results in an elevation of the cage, but in this case the slack in the chain is found on the drum side. Should a collision occur while the cage is in motion, the attendant gate movement would result in winding or unwinding the chain on the drum. Such slackening of the chain would, in itself, be of no consequence, but because of the limited space within the post and the danger of the slackened chain come into contact with some part of the electrical control mechanism, I prefer to provide means for taking up such slack. For the sake of clearness such means is shown to consist in a pair of idlers 40, 41, from which a pair of weights 42, 43 are held suspended. On these idlers are mounted guides for the chain, such guides being shown to comprise a plurality of pins 44. The weights should be heavy enough to rotate the idlers to take up any slack in the chain, but not so heavy as to interfere with the normal movement of the chain.

The statement, that the gate may be struck by an approaching vehicle without attendant damage to the gate, presupposes that the barrier 2 is made very light, strong and flexible. An ordinary barrier would, perhaps, suffer by a sudden, violent impact, but my gate is, and must be, specially designed and constructed to yield without being damaged. All the sections, except the joining section 70, may be exactly alike but gradually and uniformly diminishing in size.

Where the gate is used to close the entrance to private property, it is seen that the closing of the relay circuit by an approaching vehicle operates to open the gate for the passage of this vehicle. The drawings are merely illustrative of my invention, no attempt having been made properly to proportion the structure, this being the function of a competent engineer. I only wish to state that, the lighter and more flexible the gate barrier is, the less the danger of damaging the gate and the cheaper the whole structure may be made.

I claim:

1. In a gate, the combination with a tubular post, of a barrier hung on said post, a cage vertically slidable within the post to swing said barrier back and forth, a power circuit, an electric motor in said circuit to elevate said cage, a brake, a magnet in the circuit to set said brake normally to maintain the cage elevated, a switch, elements connected with the cage to throw said switch thereby

to cut out said motor and cut in the said magnet, and a relay circuit operable by a passing vehicle to break said power circuit.

2. In a gate, a weatherproof casing, a barrier hung on said casing, a cage vertically slidable within the casing and connected to swing said barrier back and forth, a power circuit within the casing, a motor on the cage and operable by power from said circuit to raise the cage, an electrically operated brake mechanism in the cage, means for cutting out said motor when the cage is elevated and to cut in said brake mechanism to hold the cage elevated, and a relay circuit operable by a passing vehicle to break said power circuit.

3. In a gate, a tubular post, a cage vertically slidable within the post, electrically controlled means for elevating said cage to close the gate and to maintain the cage elevated, and means actuated by a passing vehicle to release the cage and permit it to sink by its own weight and to open the gate.

4. In a gate, a tubular post, a cage vertically slidable within the post, a barrier hung to swing horizontally on the post, means interconnecting said cage and barrier for simultaneous movement, said means including a drum within said cage, a sprocket wheel in the post above the cage, a chain on said sprocket wheel at one end fastened to said drum and at the other end to the cage, a power circuit, a motor in said circuit to raise the cage, an electrically operated brake mechanism in the cage, a switch in the cage, an element on the chain to throw said switch to cut out said motor and cut in said brake, and a relay circuit operable by a passing vehicle to break said power circuit.

5. In a gate, a weatherproof casing, a cage vertically slidable within the casing to move the gate, a power circuit, a motor in said circuit for elevating said cage, a brake to hold the cage elevated, a magnet in the circuit to set said brake, means to cut out the motor and cut in said magnet, an auxiliary magnet to assist in setting the brake, means operable by the plunger of said magnet to cut out this magnet after the brake is set, and a relay circuit operable by a passing vehicle to break said power circuit.

6. In a gate, a vertically disposed casing, a cage slidable within said casing, means guiding the movement of the cage, electrically controlled means for elevating the cage within the casing to close the gate, electrically controlled means for maintaining the cage elevated, and means actuated by a passing vehicle to release the cage and permit it to sink by its own weight, thereby to open the gate.

7. In a gate, a cage vertically movable to swing the gate, a sprocket wheel above said cage, a drum in the cage, a chain extending from said drum over said sprocket to the top of the cage, a power circuit, means in said circuit for turning said drum to elevate the

cage and to maintain it elevated, a relay circuit operable by a passing vehicle to break said power circuit, thereby to permit said cage to fall until said chain is unwound, the gate being free to yield to external pressure in either direction, thereby turning said sprocket wheel and elevating the cage with the result that a slack develops in the chain on either side of the sprocket, and means for taking up such slack.

8. In a gate, a tubular post, a mechanism vertically movable within said post, a vertically disposed rod pivotally mounted on said post, a barrier rigidly secured to said rod, connections between said mechanism and the said rod for swinging said barrier in response to movement of said mechanism, said connections permitting the barrier to be moved by outside agencies independent of the movement of said mechanism, a power circuit controlling the movement of said mechanism, and a relay circuit operable by a passing vehicle to break said power circuit.

9. In a gate, a cage vertically movable, a barrier connected to be swung horizontally by said cage, a power circuit controlling the upward movement of the cage, means in said circuit for maintaining said cage elevated, and a relay circuit operable by an approaching vehicle to break said power circuit, thereby to permit the cage to descend.

In testimony whereof I have hereunto affixed my signature.

HENRY DOESKEN.
